[57] CLAIM

The ornamental design for a female buckle portion, as shown and described.

DESCRIPTION

FIG. 1 shows a perspective view of my new design for a female buckle portion as inserted into a male buckle portion;

FIG. 2 shows a top view thereof;

FIG. 3 shows a bottom view thereof;

FIG. 4 shows a perspective view of the female buckle portion;

FIG. 5 shows a top view thereof;

FIG. 6 shows a bottom view thereof;

FIG. 7 shows a side view of the female buckle portion with a male buckle portion inserted therein, with both sides being identical;

FIG. 8 shows a front end view thereof; and,

FIG. 9 shows a rear end view thereof.

The portions shown in dotted lines are for environmental purposes only and do not form a part of the invention.
